SET UP BOX

Joseph J. Stavis, Roxbury, and Bernard H. Stavis, Newton, Mass.

Application December 2, 1952, Serial No. 323,626

5 Claims. (Cl. 229—52)

This invention relates to set up boxes of paper board or the like, particularly of the type which can be nested for shipment.

An object of the invention is to provide a nesting set up box made of paper board and having a handle formed in one of the closure flaps of the cover rather than attached separately to the cover, thereby effecting a saving of material.

Another object of the invention is to form such a box and handle with a slot for receiving the handle positioned in one of the walls of the box rather than on a special slotted flap thereby also saving considerable material.

A further object of the invention is to provide a tapered set up box with an integral handle and handle slot wherein the handle is pre-creased to more readily enter the handle slot upon closing of the box into carrying position.

A still further object of the invention is to provide a handle on a tapered set up box which handle is of double thickness above and below the handle slot, thus achieving extra strength in the areas of greatest stress.

Another object of the invention is to provide a handle on a tapered set up box which is not only of double thickness above and below the handle slot but also includes a double portion extending longitudinally beyond the ends of the handle slot.

Still another object of the invention is to provide a set up box with a hinged cover in which a closure flap of the cover serves as a supporting element for the box in non-carrying position and serves as a handle in carrying position.

In the drawing,

Fig. 1 is a plan view of the preferred form of the invention in open position.

Fig. 2 is a side elevation of the box shown in Fig. 1, in section on line 2—2 of Fig. 1, showing the manner of nesting the same.

Fig. 3 is an enlarged side elevation of the box shown in Fig. 2 with the cover closed and the handle in non-carrying position.

Fig. 4 is a view similar to Fig. 3 showing the handle in carrying position.

Fig. 5 is a front elevation of the box shown in Fig. 4 on end and in carrying position.

Fig. 6 is a fragmentary plan view similar to Fig. 1 of a modified form of handle and

Fig. 7 is a fragmentary side elevation in section, similar to Fig. 4 showing the doubled handles in bowed condition.

The preferred form of the invention is shown in Figs. 1—5 and Fig. 7 and comprises a nestable set up box B having a cover with an integral handle H. The box B includes a pair of tapered side walls 20 and 21, a pair of tapered end walls 22 and 23 and a flat bottom 25, the walls being joined at the corners such as 26 to form a set up box.

A flat cover 27 is hingedly attached to the upper edge

2

of a wall such as 23 along the line of articulation 28 and is provided with a pair of tapered side closure flaps 29 and 30, hingedly attached to cover 27 along lines of articulation 32 and 33. A tapered end closure flap 35 is hingedly attached to cover 27 along the line of articulation 36 at the free end of the cover opposite the line of articulation 28.

The handle H of the invention is integral with the tapered end closure flap 35 and forms the terminal portion thereof.

As shown in dotted lines in Fig. 1, handle H is preferably doubled, the portion 51 being formed from the same sheet of material and bent back upon the portion 52 on the line of articulation 53. As shown, portions 52 and 51 are preferably of less width than the base portion of end closure flap 35 and are shaped to form a hand grip with a finger opening such as 54 therethrough.

A terminal glue tab 58 is provided on the portion 51 and adhesively secured to the inside face 40 of end closure flap 35 by any suitable adhesive such as glue. The portions 52 and 51 are of the same width as an elongated slot S formed centrally in the wall such as 22 opposite to the wall to which cover 27 is attached. Preferably the glue tab 58 is of greater width than the slot S, or the handle H, as indicated at 59 and 60.

Thus, as shown in dotted lines in Fig. 5, tab 58 extends longitudinally beyond the ends of the slot S and distributes the stress on the line of articulation 70 of the handle when the box B is filled.

Handle H is preferably pre-creased on its line of hinged attachment 70, by any suitable well known mechanism during the manufacture of box B, whereby handle H may be bent outwardly from flap 35 from its normal position in extension thereof. When the cover 27 is being closed with the side closure flaps 29 and 30 and the end closure flap 25 tucked inside walls 20, 21 and 22, the edge at 53 of handle H thus bears against the inside face of wall 22 and springs into the slot S. Handle H may then be drawn further through slot S until in the carrying position shown in Figs. 4 and 5, in which position the cover 27 is locked to the receptacle portion of box B.

In its normal position shown in Fig. 3, which is called herein the non carry position, handle H is in extension of the remainder of flap 35 and serves to support the cover on the box in the same manner as the side closure flaps 29 and 30.

It should be noted that end flap 35 with its doubled handle H is equal in depth to the depth of the front wall 22 of the box, and that the side closure flaps 29 and 30 are equal in depth to the depth of the side walls 20 and 21 of the box. Thus both the side closure flaps 29 and 30 and the end closure flap 35 reach, and are supported on the box bottom 25 when the cover is closed in non carry or storage position. When the boxes of this invention are filled with shoes or the like and stacked one upon the other, the covers 27 of each box are supported entirely around the box and do not sag or collapse.

As indicated in Fig. 7, the doubled portions 51 and 52 of handle H may be bent into bowed form in which position they tend to prevent accidental withdrawal of handle H from the slot S. For withdrawal or insertion, the portions 51 and 52 are pressed flatwise together and easily passed through slot S.

A modified form of the invention is shown in Fig. 6 wherein the handle 200 of a box 202 is not doubled, but is formed from an end closure flap 201 and connected thereto by the line of articulation 203. The end closure flap 201 is hingedly connected to a cover 227, similar to 27 and the other parts of the box 202 are similar to box B including a slot such as S for the handle 200.

As indicated in Fig. 2, it will be noted that the ta-

3

pered set up boxes B, each formed of sheet material and having a handle H and handle slot S may be nested for shipment. As indicated in Fig. 3 the boxes B may be filled and the cover closed while resting on the shelves of a store without handle projecting to take up space. As indicated in Figs. 4 and 5 when the box and its contents are sold the handle H is inserted in slot S so that the cover is not only locked to the box, but the customer can carry the box by the handle. The box B is thus not only useful as a shipment container for articles such as shoes or the like, but may be used by the customer as a hand bag, knitting bag or similar hand carried receptacle for a long period after purchasing the article contained therein.

We claim:

1. A nestable set up box of bendable, resilient sheet material, said box comprising a pair of tapered side walls; a pair of tapered end walls; a flat bottom; a flat cover hingedly attached at one end to one of said walls; a pair of tapered side closure flaps hingedly attached to said cover; a tapered end closure flap hingedly attached to the free end of said cover and equal in depth to the depth of the walls of said box to receive support from the box bottom; a doubled handle having a terminal glue tab adhesively secured flatwise on the inside face of said end closure flap, and forming the terminal portion of said end closure flap, said handle having a finger opening therethrough, and a handle slot, centrally positioned in the wall of said box, opposite to the wall to which said cover is attached, said slot being arranged to receive said handle when the cover is closed.

2. A set up box as specified in claim 1 wherein said terminal glue tab is of greater width than said handle and slot for resisting fracture of the base of said end closure flap in extension of the edges of said handle.

3. A nestable set up box of bendable, resilient sheet material, said box comprising a pair of tapered side walls, a tapered rear wall, a tapered front wall having

5
10
15

a laterally extending handle slot intermediate of the height thereof; a flat bottom; a flat cover hingedly attached along the top of said tapered rear wall; a pair of tapered side closure flaps hingedly attached to said cover and adapted to be supported on the box bottom when the cover is closed and a tapered end closure flap hingedly attached to the free forward end of said cover, said end closure flap having an integral, reversely tapered, doubled portion folded back and adhered thereto in overlying flatwise position, said doubled portion being cut out to form a doubled handle with parallel longitudinally extending side walls adapted to fit within said slot and said tapered end flap, with its doubled handle, being adapted to be supported on the box bottom when the cover is closed.

20
25
30

4. A combination as specified in claim 3 wherein said doubled end closure flap is pre-creased laterally at the base of said handle and said handle is pre-folded on said crease line into an angular position relative to the base of said flap for causing the leading edge of the handle to engage in said slot when the cover is being closed.

5. A combination as specified in claim 3 wherein the plies of the handle portion of said end closure flap are in bowed formation whereby the bowed handle may be squeezed flatwise to pass through said slot but resume said bow after such passage.
